(57) **CLAIM**

We claim the ornamental design for a mountable power receptacle, as shown and described.

DESCRIPTION

FIG. 1 is a front, upper perspective view of a mountable power receptacle showing our new design;

FIG. 2 is a rear, upper perspective view thereof;

FIG. 3 is a rear, lower perspective view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof; and,

FIG. 9 is a bottom plan view thereof.

In the drawings, the broken lines depict portions of the article that form no part of the claimed design. The flexible power cords and housing of the mountable power receptacle are also shown with break lines illustrated to indicate a symbolic break in the respective lengths of the design thereof. The appearance of any portion of the article between the break lines forms no part of the claimed design.
